UNITED STATES PATENT OFFICE.

THOMPSON EDWIN GARSUCH AND THOMAS JONES, OF VIOLA, WISCONSIN.

MITER-BOX.

SPECIFICATION forming part of Letters Patent No. 318,464, dated May 26, 1885.

Application filed January 4, 1884. Renewed April 30, 1885. (No model.)

To all whom it may concern:

Be it known that we, THOMPSON EDWIN GARSUCH and THOMAS JONES, citizens of the United States, residing at Viola, in the county 5 of Richland and State of Wisconsin, have invented a new and useful Improvement in Miter-Boxes, of which the following is a specification, reference being had to the accompanying drawings.

10 This invention relates to an attachment for miter-boxes, especially of the Langdon class, and the objects of the same are to provide suitable adjustable means for holding molding material of different widths in position while 15 being sawed, and to provide a measuring-scale properly graduated, by means of which the exact length of molding may be readily ascertained and a uniformity of length in the manufacture of picture-frames obtained.

20 With these and other objects in view our improvements consist in the attachment and its adjuncts, as will be hereinafter more fully set forth.

In the annexed drawings, Figure 1 represents our improvements in connection with the 25 outlines of a Langdon miter-box, and Fig. 2 is a plan view of the attachment.

A represents a triangular-shaped box-frame, composed of the bed-piece B and the back 30 C, mounted upon suitable supports. The adjacent end of the back C is shouldered to form a flush connection with the back of the miter-box.

To the inner edge of the bed-piece B is arranged a scale bar or strip, E, properly graduated to inches and fractions thereof and extending from right to left; also the upper surface of the bed-piece is graduated with diagonal lines arranged at an angle of forty-five 35 degrees, to register with the scale on the scale-bar E, as shown. By means of the graduated scale-bar, in connection with the graduated bed-piece, much trouble and annoyance are obviated in ascertaining the proper length and 40 miter-joint for the desired cut.

The block D, placed transversely under the

legs of one end of the miter-box and the legs of the adjacent end of the miter-box attachment, is to make them level with each other.

To the bed-piece B is attached the stop gage 50 or rest F, provided with an elongated transverse slot, a, through which passes a thumb-screw bolt, b, said thumb-screw bolt being secured firmly on the underside of the bed-piece by means of a nut. This stop gage or rest, 55 which is preferably triangular in shape, is made of wood or other suitable material, and by means of the elongated slot a is adapted to be adjusted to moldings of different widths.

After the desired length to be sawed has 60 been ascertained by the graduated scale on the bed-piece the molding is moved forward and clamped in position by the adjustable gage F, thus securing a solid sawing means.

When other material than molding is to be 65 sawed, the stop gage or rest F and its fastening means are removed, and the attachment is in condition for wide boards or very wide molding.

The graduated scale-bar being flush with 70 the bed-piece, or forming an integral part thereof, does not interfere with the sawing or in its attachment to a miter-box.

What we claim is—

In an attachment for miter-boxes, the combination, with the bed-piece B, having scale-graduations corresponding with the scale-graduations on a scale-bar, E, at the front of the bed-piece provided at its rear edge with the back-piece C, of the triangular stop-gage 75 F, slotted transversely at a, and removably and adjustably secured to the scaled bed-piece by the thumb-screw bolt and nut d b, substantially as specified.

In testimony that we claim the foregoing as 80 our own we have hereto affixed our signatures in presence of two witnesses.

THOMPSON EDWIN GARSUCH.
THOMAS JONES.
